CLAIM

We claim the ornamental design for a cellular phone, as shown.

DESCRIPTION

FIG. 1 is a top, right side, and front perspective view of a cellular phone, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.
